UNITED STATES PATENT OFFICE

2,100,064

INTERNAL COMBUSTION ENGINE

Alvin K. Zimmerman, Akron, Ohio

Application May 1, 1934, Serial No. 723,373

6 Claims. (Cl. 123—59)

My invention relates generally to internal combustion engines, and particularly to an engine of this type in which the combustible charge is compressed in a charge compressing cylinder or cylinders and then fed to the combustion chamber or working cylinders, and an important object of my invention is to provide an internal combustion engine of the type indicated which is highly simplified and efficient.

It is also an important object of my invention to provide in an internal combustion engine of the character indicated a two-cycle charge compressing unit and a four-cycle working unit, thereby greatly increasing the compression of the charge before it is fed to the working cylinders and more favorably vaporizing the same.

Other objects and advantages of my invention will be apparent from a reading of the following description in connection with the drawings, wherein for purposes of illustration I have shown a preferred embodiment of my invention.

In the drawings:—

Figure 1 is an elevational view of the right hand side of the embodiment.

Figure 2 is a transverse vertical sectional view taken through Figure 1 approximately on the line 2—2 and looking rearwardly in the direction of the arrows.

Figure 3 is another transverse vertical sectional view taken through Figure 1 approximately on the line 3—3.

Figure 4 is a top plan view of Figure 1.

Figure 5 is a transverse sectional view through one of the wrist pins, showing the manner of connecting the upper end of the connecting rod thereto.

Figure 6 is a transverse vertical sectional view through a portion of the valve mechanism.

Figure 7 is a horizontal sectional view through one of the pistons.

Figure 8 is a diagrammatic representation of and showing the relationship of the two-cycle and four-cycle cam shafts.

Referring in detail to the drawings, the numeral 5 generally designates the oil pan which depends from the crankcase 6 from which rises the cylinder block 7, the top of which is closed by the cylinder head 8. The numerals 9, 10 represent the valve chamber covers of the working part of the engine and of the charge compressing part, respectively.

The crank shaft projects forwardly and rearwardly from the bearing structures 11, 12, respectively, formed on opposite sides of the point of separation of the crankcase and the oil pan, and

on its rear end has the flywheel 13 and on its front end the fan belt driving pulley 14 which has trained thereover the fan belt 15 which is also trained over the fan pulley 16 on the fan shaft 17 which is also the impeller shaft for the water pump 18 which is mounted as indicated on the front end of the cylinder head 18 and combined with the cooling water outlet 19. The fan 20 is fixed on the front end of the fan shaft 17.

The exhaust pipe 21 has the vertical portion 10 25 and another branch leading from the same point thereof and indicated by the numeral 26 is a portion of the exhaust manifold 27 of the working portion of the engine. The intake manifold 28 which feeds only the compressing part of the engine has the depending portion 29 to which is connected a suitable carburetor (not shown).

The oil pan 5 has supported therein above the bottom the tray 30 which has the depressions 31 under the throws of the crankshaft so as to form sub-reservoirs in which the lower end of the connecting rods 32 work and use their cups or vanes 33 to throw and splash the oil in the crankcase to the bearings.

Web 34 of double fan-shape are arranged across the lower portion of the crankcase 6 to provide the upper bearing for the crank shaft, the lower part of these bearings being constituted by removable caps 35 which are bolted to the corresponding webs 34 as indicated at 36.

At the right hand side of the crankcase at the top thereof are the inwardly projecting brackets 37 supporting the cam shafts 38, 43. The cam shaft 38 operates the valves of the working part of the engine. The front end of the cam shaft 38, has fixed thereon the pinion 42' which is in mesh with the idler pinion 41' which is in turn in mesh with the gear 40' on the front end portion of the crankshaft 44. The cam shaft 43 operates the valves in the compressing part of the engine. It is arranged that the cam shaft 43 will be operated at the same rate of rotation as the crankshaft, while the cam shaft 38 rotates only once for every two revolutions of the crankshaft 44. The gears or pinions 40, 41 and 42 may be of any suitable material such as the composition material now generally used for gears of this type, so that the gears will be silent and long-wearing. The idler gears 41 and 41' are suitably supported within the crankcase as indicated. The crankshaft gear 40' is only half the size of crankshaft gear 40.

The working portion of the engine, particularly shown in Figure 3, comprises within the motor block 7 and head 8 the water jacket 45, the spark 55

plugs 46 leading into the top of the cylinder head or combustion chamber 47 in which work the pistons connected by the connecting rod 32 to the corresponding throws of the crankshaft 44. The 5 lower end of each connecting rod 32 has an upper bearing portion 15 and a lower bearing portion 51 which are bolted as indicated at 52 to confine a removable bearing 53.

The upper end of each connecting rod in the 10 engine is connected to the wrist pin 53 of each of the pistons in the manner indicated in Figure 5. The upper end of the connecting rod is circular as indicated at 54 and is split at one side as indicated at 55 to provide the upper and lower 15 furcations 56, 57 which are arranged to be clamped together by a bolt 58 which traverses them. A notch 59 in the adjacent side of the wrist pin 53 is engaged by the bolt 58 so as to lock the wrist pin against turning relative to the connecting 20 rod, and to lock the wrist pin against moving longitudinally or axially relative to the connecting rod. As shown in Figure 7 a simplified form of piston is used which has the wrist pin supporting members 60 and 61 whose aligned bores have 25 bushings 62, 63 of removable type which are flanged as indicated at 64, 65 and their inward ends provide shoulders which act as bearings presented to the opposite sides of the portion 54 of the connecting rod.

30 The valves 66 leading to the pump cylinders are of the mushroom type and include the stem 67 which works through a solid guide portion 68 in the upper part of the motor block, the lower part of the stem working in the valve chamber 69 35 where a helical spring is circumscribed thereon and works between the top of the chamber and a cup-shaped retainer 71 which is held in place by a washer 72 locked by a pin 73 and presenting its lower end to the tappet 74 which works through 40 the removable bushing 75 seated in an appropriate opening in the lower wall of the valve chamber and extending into the crank case, as shown in Figure 6, to be operated by the cam shaft 38. It is to be noted that the cam shafts 38 and 43 are 45 axially aligned and spaced, and as already pointed out these cam shafts are in a 2 to 1 speed ratio of rotation.

In the embodiment shown the working portion 50 of the engine includes four cylinders 76 in line, while the compressing portion comprises two larger cylinders 77 in line and aligned with the working cylinders. The exhaust 78 of the compressing part of the motor discharges into a manifold 79, which is the intake manifold for the 55 working part of the engine.

The compressing cylinders with their pistons 80, connecting rods 81, wrist pins 82, connecting rod bearings 83, and water jackets 84 are generally similar in structure and arrangement to 60 the corresponding parts of the working part of the engine.

Instead of having exhaust valves in the upper part of the motor block as in the ordinary L-head type of motor as obtains in the case of the working parts of the engine, the exhaust valves 85 of the compressing part of the engine seat in openings 86 in the central portion of the head 8 and have their stems 87 rising above the heads and threaded as indicated at 88 and slotted as indicated at 89. The smooth part of the stem 87 works through the web 90 of the hollow housing 91.

An extension 92 of the stem 87 which is adjustably connected to the upper end of the stem 75 87 works in the portion of the housing above the

web or partition 90 and encircling this extension is the valve spring 93 which works against the top of the housing and against the retainer structure generally designated 94. Each of the two compressing cylinders 77 has a housing 91 with 5 the valve mechanism described, and a discharge conduit 95 leading from the lower part thereof and joining the branch 23 of the exhaust manifolds 78 and 79. The branch 25 of the exhaust pipe 21 leads to a smaller conical housing 96 10 which is supported at one side of the working part of the engine as shown in Figure 3. Within the housing 96 is a valve 97 working against the seat 98 in the lower part of the housing and having the extension 99 working in the upper part of the housing and pressed to seat by the spring 100 working against the retainer 101, and the housing is mounted on the upper side of the intake manifold 79. The housing 96 and its attendant mechanism operates as a safety valve in case of 20 back fire, to by-pass the back fire into the exhaust pipe 21, the increased back-pressure consequent upon a back fire being adequate to open the valve 97 to permit the back fire to pass to the exhaust pipe 21. This arrangement prevents 25 back firing into the compressing part of the engine, which is necessary for safety and proper operation of the compressing part of the engine.

Giving the cylinders numerals from front to back, the firing order is as follows:—

(1)	(2)	(3)	(4)	(5)	(6)
F	S	C	E	C	S
S	C	F	S	O	S
C	E	S	F	S	C
F	S	C	E	O	S

Note:—F=Firing.
S=Suction stroke.
C=Compressing stroke.
E=Exhaust stroke.

It will also be noted that compression cylinder 5 supplies the charge for working cylinders 1 and 2 while compressing cylinder 6 supplies the charge 45 for working cylinders 3 and 4, during the operation of the engine continuously; and that while the respective piston in the working part of the motor is down, the related large piston of the compressing part is up; and the charged small cylinder or working cylinder has the amount of gas which was previously contained in the large or compressing cylinder. In order to operate to the greatest efficiency it is found that long stroke pistons of relatively small diameter in the working part of the engine are advisable to take care of the relatively enormous expansion of the highly compressed charge therein, which is further compressed by the action of the working piston. It will be observed that the course of the charge from the point of its introduction into the compression unit to the combustion chambers is of such duration that an unusual opportunity is presented to vaporize and to be completely vaporized when finally delivered to the working cylinders. The cam shaft of the compression part of the engine makes one revolution to each revolution of the crankshaft, while the cam shaft for operating the exhaust and intake valves of the working part of the engine rotates at half the rate of rotation of the other camshaft. The valve mechanisms housed by the housings 91 act as safety valves and are closed by backfire pressure thereby preventing the backfire from reaching the compression cylinders.

Each of the compressing cylinders has an intake and an exhaust valve similar in structure to the valves in the working part of the engine, and the compression part valves are operated by the 5 cam shaft 38, the working part valves being operated by the cam shaft 43, the intake valves receiving the gas from the carburetor through the intake manifold 28 and the exhaust valves discharging through the working part intake manifold 10 fold 19.

It will be obvious that in case of a back fire or excess pressure in 18 and 19 the pressure therein will open the valve in the housing 96 and will close also the valves 85 in the housings 91, thereby 15 creating a situation in which the only path of escape of the back fire is through 25 and into the exhaust pipe 21.

A suitable type of relief valves 102 is provided in the head to release the pressure within the 20 compression cylinders 77 when starting the engine. Otherwise, the relatively weak starting impulses of the engine would not be equal to operating the compressing pistons. The valves 102 are connected by an operating link 103, and a second 25 operating link 104 on a shaft 105 which has another crank operated by a control lever 106. After the engine is running the valves 102 are closed to seal the cylinders 77.

Although I have shown and described herein a 30 preferred embodiment of my invention, it is to be definitely understood that I do not desire to limit the application of the invention thereto, and any change or changes may be made in material and structure and arrangement of parts, within the 35 spirit of the invention and the scope of the subjoined claims.

What is claimed is:—

1. In an internal combustion engine of the character described having a cylinder block containing working cylinders and compression cylinders, each of the working cylinders having an exhaust and an intake valve and each of the compression cylinders having an exhaust valve and an intake valve, a carbureted gas supply to the compression cylinders, an intake manifold for said working cylinders, an exhaust conduit to which said working cylinders discharge, and a safety valve on said intake manifold arranged to discharge to said exhaust conduit.

50 2. In an internal combustion engine of the character described having a cylinder block containing working cylinders and compression cylinders, a crankshaft supported in connection with the cylinder block, pistons in the working cylinders and in the compression cylinders operatively connected to said crankshaft, each of the working cylinders having an exhaust and an intake valve and each of the compression cylinders having an exhaust valve and an intake valve, a first 55 cam shaft for operating the valves of the working cylinders, and a second cam shaft for operating the valves of the compression cylinders; a carbureted gas supply to the compression cylinders, an intake manifold for said working cylinders, and means for firing the charge in the working cylinders, said intake manifold having a safety exhaust valve, said engine having an exhaust conduit to which said safety valve is connected; and a safety valve for each of the compression cylinders discharging to said exhaust pipe, and arranged to be closed by excessive pressure present in said exhaust pipe.

70 3. In an internal combustion engine of the character described having a cylinder block containing working cylinders and compression cylinders,

ders, each of the working cylinders having an exhaust and an intake valve and each of the compression cylinders having an exhaust valve and an intake valve, a carbureted gas supply to the compression cylinders, an intake manifold leading from said compression cylinders to said working cylinders, an exhaust conduit to which said working cylinders discharge, and a safety valve on each compression cylinder arranged to discharge to said exhaust conduit.

5 4. In an internal combustion engine of the type described comprising a working cylinder including an intake and an exhaust valve, a compressing cylinder including an intake valve and a first exhaust valve and a second exhaust valve, a manifold connecting the compressing cylinder first exhaust valve with the working cylinder intake valve, a second manifold leading from the said second exhaust valve and the exhaust valve of the working cylinder, a safety valve communicating with said first manifold, a conduit leading from said second manifold to said safety valve, a second conduit leading from said second manifold and communicating with said first exhaust valve, said safety valve and said first exhaust valve being resiliently seated and arranged to be closed by excessive pressure present in said second manifold.

10 5. In an internal combustion engine comprising working cylinders and compressing cylinders, each of said cylinders having an intake valve and an exhaust valve, a fuel manifold connecting all of the compressing cylinders with some of the working cylinders, an exhaust manifold leading from said working cylinders, first safety valve 35 means in communication with said compressing cylinders and said exhaust manifold, second safety valve means communicating with said fuel manifold and with said exhaust manifold, the first and second safety valve means being normally resiliently closed and arranged to open upon development of excess pressures in said working cylinders and in said fuel manifold, respectively, and arranged to be opened by excessive back pressure in said exhaust manifold.

20 6. In an internal combustion engine comprising working cylinders and compressing cylinders, each of said cylinders having an intake valve and an exhaust valve, a fuel manifold connecting all of the compressing cylinders with some of the 40 working cylinders, an exhaust manifold leading from said working cylinders, first safety valve means in communication with said compressing cylinders and said exhaust manifold, second safety valve means communicating with said fuel manifold and with said exhaust manifold, the first and second safety valve means being normally resiliently closed and arranged to open upon development of excess pressures in said working cylinders and in said fuel manifold, respectively, and arranged to be opened by excessive back pressure in said exhaust manifold, said first and second safety valves each comprising a casing having one end surrounding a valve opening in the corresponding cylinder or fuel manifold, a web across the casing, a valve stem slideable therethrough and having a head cooperating with the corresponding valve opening, a spring on each stem and engaged between one end of the casing and a portion of said stem, and 45 a side port in the casing axially inwardly of said web and axially outward of said valve head, said port being connected with said exhaust manifold.
